UNITED STATES PATENT OFFICE

JAMES PICKFORD, OF OLDHAM, ENGLAND

GUARD FOR CARDING ENGINES

Application filed July 31, 1930, Serial No. 472,144, and in Great Britain August 15, 1929.

This invention relates to improvements in mechanism for locking the doors of carding engines such mechanism being of the type in which the opening of the door is controlled by a sliding bar which is locked by a loose disc or roller situated in a stationary casing and maintained just clear of the cylinder so that when the latter is in rotation it cannot be moved to unlock the bar, such unlocking being only possible when the cylinder is at rest.

In mechanism of this type as hitherto constructed the locking roller or disc was wholly encased within the stationary casing and was operated by a second loose roller or disc arranged in the same plane as the locking roller or disc and engaging the periphery thereof. This loose roller or disc projected through the front of the casing so that when the cylinder was at rest the rotation of the loose roller caused the locking roller to rotate and rise out of engagement with the sliding bar so that the latter was free to slide longitudinally and the door of the carding engine could be unlocked.

A disadvantage of such locking mechanism lay in the fact that it was possible for the device to be operated when the cylinder was rotating and another disadvantage lay in the fact that it was only applicable to certain types of carding engine since the strap obstructing bar, which prevents the driving belt from being moved on to the fast pulley until the cylinder door is closed, was mounted on the stationary casing at the side adjacent to the pulley. A further disadvantage lay in the fact that if the locking roller was set too far away from the side of the cylinder it did not lock the bar.

The object of the present invention is to provide a simpler construction of locking device which cannot be operated when the cylinder is rotating and which will permit of the strap obstructing bar being pivoted on the side of the casing remote from the pulley so that the device can be applied to any type of carding engine.

The invention consists of a single locking roller or disc located in a casing having an aperture above the central axis of the roller

or disc such aperture being sufficiently large to allow access to the periphery of the roller by a finger or fingers only so that the roller or disc cannot be gripped between the fingers, but when the cylinder is at rest it can be readily rotated to cause it to rise out of engagement with the sliding bar.

The invention consists further in pivoting a cam member which oscillates the strap obstructing rod on the side of the casing remote from the driving pulley the end of the sliding bar being provided with a raised or ramp surface to oscillate the cam when the bar is withdrawn, such raised or ramp surface being in front of the surface on which the roller or disc rests when it has been raised out of the locking aperture at the front of the bar and the bar has been moved forward to the door to be opened.

By this construction of locking device the sliding bar connects the arm of the cylinder door directly to the casing and no additional brackets or studs are necessary to carry the strap obstructing bar.

The invention will be described with reference to the accompanying drawings:

Fig. 1 is side view of part of a carding engine showing the casing carrying the single locking roller bolted to the framing, the sliding bar being in the position occupied when the door is open.

Fig. 2 is a section on line 2—2 Fig. 1.

Fig. 3 is a side elevation of part of a carding engine showing the casing bolted to the bend, the sliding bar being in the position occupied when the door is closed.

Fig. 4 is a section on line 4—4 Fig. 3.

Fig. 5 is a perspective view of casing, locking roller, end of one form of sliding bar and a strap obstructing rod.

Fig. 6 is a perspective view of end of another form of sliding bar.

Fig. 7 is a vertical section through the casing and locking roller.

Fig. 8 is a section on line 7—7 Fig. 7 showing the casing bolted to the bend of the carding engine.

The stationary casing B is bolted to the framing A of the carding engine as shown in Figs. 1 and 2 or to the bend a as shown in

- Figs. 3 and 4 according to the type of carding engine to which it is applied. A loose roller C is located within the casing B and contacts at *c* with the side of the cylinder A¹.
- 5 In the form of the invention shown in Figs. 3 and 4 the strap obstructing member G is of ordinary construction and is arranged on the side of the casing B adjacent to the fast and loose pulley.
- 10 In the form of the invention shown in Figs. 1 and 2 the member G is mounted on the side of the casing B remote from the fast and loose pulley, its construction and operation being hereinafter more fully described.
- 15 An aperture *b* is formed in the front of the casing B such aperture being above the central axis of the roller C when the latter is in its lowest or locking position, i. e. the position shown in Fig. 7. The periphery of the roller C is level with and projects a very short distance into the aperture *b* so that it can be engaged by the finger or fingers of the operator but cannot be gripped between the fingers.
- 20 A transverse slot, groove or passage *b*¹ is formed at the bottom front edge of the casing B to form a guide and support for the sliding bar D which is pivotally connected at its end *d* with the pivoted arm E supporting the cylinder door E¹. The front end of the bar D is formed with a recess *d*¹ which is engaged by the roller C when the bar is in the locking position so that the bar cannot be moved until the roller C is rolled upwards to raise it out of the slot.
- 25 When the strap obstructing member G is of ordinary construction and is mounted on the side of the casing B adjacent to the fast and loose pulley the recess *d*¹ extends across the bar D and as shown in Figs. 3 and 4 the upper surface of the end of the bar is raised and is formed with an incline *d*² so that after the roller C has been raised it will not return to its original position as the bar D is moved. The front end of the bar D engages the strap obstructing member G as the rod is moved to move the member G into the obstructing position.
- 30 When the strap obstructing member G is located on the side of the casing B remote from the fast and loose pulley the end of the bar D is constructed as shown in Fig. 5 or Fig. 6 the recess *d*¹ extending to the front of the bar D as shown in Fig. 5 or only part way across the end as shown in Fig. 6.
- 35 The bar D may be formed with two top surfaces *d*², *d*³ as shown in Fig. 5, the front surface *d*² being the surface which engages and operates the cam F which controls the strap obstructing bar G and the surface *d*³ being the surface against which the roller C rests after it has been raised out of the recess *d*¹ and the bar D has moved into the unlocking position. The surface *d*² comprises a low surface *d*⁴ with which the cam engages when the bar D is in the locking position, a steep rise *d*⁵ which rotates the cam F as the bar is being moved and a raised surface *d*⁶ which holds the cam F in the position to cause the strap obstructing member G to be in the position to prevent the strap being moved on to the fast pulley whilst the door is unlocked. The surface *d*³ has a gradual downward slope *d*⁷ to the horizontal position *d*⁸ extending rearwardly of the bar so that after the roller C has been raised the latter will gradually return to its bottom position as the bar D is moved forward from the locking to the unlocking position.
- 40 In carding engines where there is only a limited space the end of the bar D may be constructed as shown in Fig. 6 in which construction the surface *d*³ only extends to the end of the slope *d*⁷. This construction allows the front surface of the rod and the strap obstructing member G to be brought further forward away from the side of the machine which is necessary for certain types of carding engines. Two brackets or lugs *b*² are formed on the side of the casing B remote from the driving pulley and carrying a short shaft *g* on which the strap obstructing bar G is mounted. A cam F is also mounted on this shaft *g* which cam is in engagement with the surface *d*² of the sliding bar D.
- 45 The construction of the end of the locking bar D as shown in Figs. 5 or 6 ensures that the roller C will always lock the bar in whatever position the latter may be set in relation to the side of the carding engine.
- 50 The locking device operates as follows:—
- When the door E¹ is closed the roller C is situated in the recess *d*¹ at the end of the sliding bar D and the cam F is in engagement with the low portion *d*⁴ of the surface *d*² so that the strap obstructing bar G is in the position to allow the strap to be moved on to the fast pulley. If the cylinder A¹ is rotated the frictional contact therewith of the roller C which would occur on any attempt by the operator to rotate the roller C, is too great to allow the latter to be rotated by a finger or fingers of the operator to cause it to be raised out of the recess *d*¹ and accordingly the bar D is locked and the door E¹ cannot be opened.
- 55 When the cylinder A¹ is at rest the roller C can be rotated by the finger or fingers of the operator to cause it to roll on the cylinder A¹ and rise out of the recess *d*¹ in the bar D and the bar can then slide through the casing B and allow the door E¹ to be opened. This movement of the bar D causes the cam F to mount up the steep incline *d*⁵ and consequently to rotate so that the shaft *g* rotates in the lugs *b*² and the strap obstructing bar G moves into the position to prevent the strap from being moved on to the fast pulley. The cam F and strap obstructing bar G remain in this position until the bar D has been returned to its locking position so

that the strap cannot be moved on to the fast pulley and the cylinder rotated until the door E¹ has been closed.

What I claim as my invention and desire 5 to protect by Letters Patent is:—

1. Guards for carding engines of the type referred to comprising the combination with a pivoted arm and a door carried thereby of a bar connected to the pivoted arm, a stationary slotted casing through which the bar slides, a locking roller engaging the bar and housed within the casing to project therefrom at both ends and prevent movement of the bar when the cylinder is rotating, a strap 10 obstructing member and a cam carried by the strap obstructing member to bear upon the bar, the strap obstructing member preventing movement of the strap until the door is closed.
2. Guards for carding engines of the type referred to comprising the combination with a pivoted arm and a door carried thereby of a transversely recessed bar, a stationary slotted casing through which the bar slides, a locking roller engaging the bar and housed 15 within the casing to project therefrom at both ends and prevent movement of the bar when the cylinder is rotating, a strap obstructing member and a cam carried by the strap obstructing member to bear upon the bar the strap obstructing member preventing movement of the strap until the door is closed.
3. Guards for carding engines of the type referred to comprising the combination with a pivoted arm and a door carried thereby of a transversely recessed bar, a stationary slotted casing through which the bar slides, a locking roller engaging the bar and housed 20 within the casing to project therefrom at both ends, a strap obstructing member, bearings on the side of the casing, a shaft carried in said bearings upon which the strap obstructing member is pivoted and a cam on 25 said shaft to bear upon the bar.
4. Guards for carding engines of the type referred to comprising the combination with a pivoted arm and a door carried thereby of a transversely recessed double surfaced bar, a stationary slotted casing through which the bar slides, a locking roller engaging the back surface on the bar and housed within the casing to project therefrom at both ends, a strap obstructing member, bearings on the 30 side of the casing, a shaft carried in said bearings upon which the strap obstructing member is mounted and a cam on said shaft bearing upon the front surface of said bar.

In testimony whereof I have hereunto set 35 my hand.

JAMES PICKFORD.
